UNITED STATES PATENT OFFICE.

CLARENCE D. TUSKA, OF HARTFORD, CONNECTICUT.

VARIOCOUPLES.

Application filed June 17, 1922. Serial No. 569,084.

To all whom it may concern:

Be it known that I, CLARENCE D. TUSKA, a citizen of the United States, residing at Hartford, in the county of Hartford, and ⁵ State of Connecticut, have invented new and useful Improvements in Vario-couplers, of which the following is a specification.

The present invention has reference to vario-couplers, vario-meters and the like ¹⁰ such as are used for varying the inductive relation between coils of radio circuits.

One object of the invention is to provide certain new and useful improvements in such devices tending to simplify their ¹⁵ construction, to facilitate the assembly of their parts, and to otherwise adapt the apparatus for economical quantity production.

With these and other objects in view, as will appear from the following specification, ²⁰ the invention resides in the features of construction and in the combinations and arrangements of parts hereinafter described and claimed, the advantages of which will be obvious to those skilled in the art.

²⁵ In the particular embodiment shown in the drawings the invention is shown as applied to a vario-coupler.

In the drawings:

³⁰ Fig. 1 is a plan view of a vario-coupler constructed in accordance with the present invention;

Fig. 2 is a sectional view taken along the line 2—2 of Fig. 1;

³⁵ Fig. 3 is a view, in end elevation, of a portion of the vario-coupler;

Fig. 4 is a plan view of a portion of the stationary tubular frame for supporting the primary winding;

⁴⁰ Fig. 5 is a fragmentary plan view of the rotor shell which supports the secondary winding;

Fig. 6 is a detail view, in perspective, of a portion of the supporting panel showing one of the lugs upon which the coupler is ⁴⁵ mounted; and

Fig. 7 is a view, in central vertical section, showing a modification of the coupler illustrated in Figs. 1 and 2.

Referring to Figs. 1 and 2 of the drawings ⁵⁰ the primary or stationary winding of the coupler is shown at 1 and the secondary or movable winding at 2. The primary winding 1 is wound upon a stator or tubular supporting frame 3 and is provided with the usual taps 4 (Fig. 1) leading to the con-

tacts of a multipoint switch 5 such as is generally employed to vary the number of active turns in the winding. The movable arm of the switch 5 is adapted to be connected by means of a conductor 6 with one ⁶⁰ side of the antenna circuit while the primary winding is adapted to be connected through suitable conductors (not shown) with the ground.

The secondary winding 2 is carried by a ⁶⁵ rotor 10 comprising an annular frame having a spherical exterior surface to receive the winding. The rotor frame is constructed of molded dielectric material and is provided with diametrically disposed trunnions ⁷⁰ 12 and 13 which have their inner ends molded in the rotor frame and thus securely anchored therein. The rotor trunnions 12 and 13 extend at right angles to the axis of ⁷⁵ the stator shell 3 and are journaled in bearing sleeves 14 and 15 carried by and electrically connected with conductors 16 and 17, the latter being in the form of flat metal straps which are rigidly secured to the stator frame. Thus, the conductor ⁸⁰ straps 15 and 16, in addition to conducting the current, serve also to maintain the stator and rotor in assembled relation. The stator frame is rigidly secured to the panel ⁸⁵ 12 by means of screws 18 and 19 which extend through the conductor strap 16 and which may be removed to permit the detachment of the coupler from the panel. When the coupler is thus detached from the supporting panel the rotor and stator will ⁹⁰ remain in assembled relation and may be handled as a unit, as will hereinafter appear.

The stator shell 3 is molded with an enlargement 20 at one end providing an annular shoulder 21 which functions to engage the outermost turn at the respective end of the primary winding to retain the same against displacement. At the opposite end of the stator shell, and at diametrically opposite points in the abuttable edge face ⁹⁵ of said end are located two semi-circular notches, one of which is shown clearly at 22 in Fig. 4, and these notches are adapted to receive the bearing sleeves 14 and 15 to locate the latter with respect to the stator shell ¹⁰⁰ 10 and to assist in maintaining the conductor straps 17 and 16 in place.

The conductor strap 16 carries the bearing sleeve 14 substantially midway between its ¹⁰⁵ ends. At one side of the bearing 14 the ¹¹⁰

- strap 16 lies in engagement with the inner peripheral face of the stator shell and extends to the shouldered end of the shell, where it is apertured to receive the screw 18.
- 5 The screw 18 extends through the strap 16 and through the stator shell and is threaded into a lug 23 that is molded upon the panel 12.
- The lug 23 has an arcuate face 24 (Fig. 6) 10 shaped to fit the curve of the stator shell for a substantial distance at either side of the fastening screw 18 to insure that the shell will be rigidly supported. At the opposite side of the bearing 14, the strap 16 extends 15 to a point above a lug 25 on the panel 12 to which lug the strap is rigidly secured by means of the screw 19 which extends through a slot 26 in the strap 16. The lug 25 is a duplicate of the lug 23, having a 20 similar arcuate face which is adapted to function as a support for an extension or duplicate of the stator shell which may be assembled with the apparatus if desired as will later appear. In the absence of such a 25 stator extension, the conductor strap 16 is fastened by the screw 19 directly to the arcuate face of the lug 25, as shown in Fig. 2, the strap being slightly offset, as shown at 27 to bring its extremity into the 30 plane of the adjacent face of the lug 25. In the assembling of the parts, should the offset 27 of strap 16 be such that the axis 12 of the rotor is not perpendicular to the panel 12, a readjustment to bring this 35 about is made possible by simply bending the free end of said strap 16 in the proper direction and securing the same in position by the screw 19. The slotted end 26 of said strap 16 will readily accommodate any such 40 adjustments in the positioning of said strap. A wire 28 which is clamped between the head of the screw 19 and the strap 27 leads to one side of the receiving circuit.
- The conductor strap 17 carries at one end 45 the bearing sleeve 15 which is adapted to fit within one of the notches 22 in the stator shell. The strap 17 extends along the inner surface of the stator shell to the thickened end of the latter where it is secured to said 50 shell by a single bolt 30. With the above described construction, wherein only a single bolt is needed to secure the conductor strap against twisting, a proportionally greater area of the stator shell may be utilized for 55 the winding than would be available if fastening bolts were employed to hold the strap at both ends of the stator shell. The strap 17 extends slightly beyond the bolt 30 and is bent at right angles for attachment to 60 another conductor 32 which is connected to the other side of the radio receiving circuit. It will be seen that the two notches 22 serve to locate the rotational axis of the rotor accurately at right angles to the axis of the 65 primary winding.

The secondary winding 2 comprises two coils 34 and 35 which are wound upon the spherically curved exterior of the rotor shell at opposite sides of the trunnions and have the usual series connection, as indicated at 36 70 in Fig. 2. The outermost turns of the coils are retained in place upon the rotor shell by means of annular shoulders 38 which are molded upon said shell. The coils 34 and 35 are separated and held out of contact 75 with the rotor trunnions by means of bosses 40 (best shown in Fig. 5) which project slightly from the spherical surface of the shell and surround the trunnions on the exterior of the rotor shell to prevent the 80 inner turns of said coils from inward lateral displacement. The bosses 40 adequately perform the functions stated and avoid the use of annular ribs or shoulders such as were heretofore generally employed between 85 the separated coils of the rotor winding for the purpose of retaining the turns of wire in place. A lead 42 (Fig. 2) from the outer turn of the coil 34 extends inwardly through an aperture in the rotor and is connected 90 with the inner end of the trunnion 12 while a lead 44 from the outer turn of the coil 35 extends similarly through an aperture in the rotor shell and is connected with the inner end of the trunnion 13.

The rotor trunnions 12 and 13 extend outwardly beyond the bearing sleeves 14 and 15 and are encircled by coiled springs 37 which bear at their inner ends against said sleeves and at their outer ends against nuts 38' and 39 which are threaded upon said trunnions respectively. The springs 37 yieldingly oppose the turning of the rotor with sufficient friction to maintain the rotor in adjusted position and they also serve to insure good electrical contact between the rotor trunnions and the conductors 16 and 17. As shown, the nut 39 is provided with a counter-bored recess 40 to receive the respective spring 37 and said nut is adapted to be 100 turned to vary the compression of the spring. The nut 38' upon the other trunnion may be tightened against a shoulder upon the trunnion and secured against turning by means of solder upon the outer face of the 110 nut.

To enable the rotor to be turned to vary the amount of the coupling between the primary and the secondary windings, the trunnion 12 is extended through an aperture 42 in the supporting panel 12 and a dial knob 45 is rigidly secured to the trunnion. Preferably, as shown, the dial knob 45 is provided with an internally screw-threaded bushing 46 which is firmly anchored in the 120 knob and is in threaded engagement with the outer end of the trunnion 12. The inner end of said bushing bears against the outer end of a bushing or collar 48 that is formed integrally with the nut 39 thus ef- 130

fectively locking the dial knob to the rotor trunnion to prevent relative turning of said knob and rotor.

It is sometimes desirable to supply various couplers with primary windings at both sides of the axis of the rotor instead of at one side only, such a coupler being commonly known as a "double tube" type. If a double tube coupler is to be assembled 10 two stator shells or "tubes" are employed these tubes being held together by conductor straps 16' and 17' (Fig. 7) the strap 16' being of the same shape and construction as the strap 16 herebefore referred to, 15 with exception that no offset is formed therein. The strap 17' extends at opposite sides of the rotor bearing carried thereby in the same manner as the strap 16'. The conductor straps 16' and 17' are provided 20 with bearing sleeves 14' and 15' for the rotor trunnions and the rotor trunnions are journaled in these bearing sleeves as already described in connection with the preferred form of the invention. Two stator shells 25 3' are then assembled with the rotor, these shells being similar in construction as the shell 3 already described, having similar notches for the reception of the bearing sleeves for the rotor trunnions. The two 30 stator shells or tubes 3' are held in assembled relation by means of dowel pins 50 which are inserted in dowel holes that are provided in the abutting edge faces of the tubes. Bolts 51 secure the stator tubes to 35 the conductor straps 17' and bolts 52 extend through the conductor straps 16' and through the stator tubes and are threaded into the lugs 23 and 25 on the panel 12, the curved faces of the tubes seating against 40 the correspondingly curved faces of the lugs 23 and 25.

By providing the two lugs 23 and 25 upon the panel 12 the latter is adapted to support a vario-coupler having either a single or 45 double tube stator as may be desired. If a double tube stator is to be assembled upon the panel, the two tubes will be dowelled together as described. It will be seen that the conductor straps 16 and 16' are the same 50 in construction except that the former has the offset 27 while the latter has no such offset. Obviously, the conductor straps may be supplied in one form only, i. e. all straps for assembly with the lugs 23 and 25 may be made straight for assembling a double tube stator and the bosses 23 and 25 will properly locate the stator so that the axis of the rotor will be perpendicular to the panel 12. If a single tube stator is to be 55 assembled, the strap 16 may be offset at 27 as shown and readily adjusted by bending the same to likewise bring the axis of the rotor to perpendicular position and the slotted end 26 will accommodate any such adjustments.

The invention has been disclosed for illustrative purposes in an embodiment at present preferred, but the scope of the invention is to be determined from the appended claims rather than from the foregoing description.

What I claim is:

1. In a device of the class described, the combination with the rotor, of a tubular stator having diametrically disposed notches in the edge face at one end thereof, trunnions carried by the rotor, bearing sleeves adapted to be located in said notches, conductor straps carrying said bearing sleeves and extending transversely across the inner periphery of the stator, and bolts severally extending through each conductor strap at the end remote from the bearing sleeve for securing the strap to the stator and holding the bearing sleeves in said notches.

2. In a device of the class described, the combination with a tubular stator and a rotor adapted to turn on an axis perpendicular to the axis of the stator, of a supporting panel, a lug on said panel having a face curved to conform to the exterior curvature of the stator, trunnions carried by the rotor, bearings for said trunnions, conductors carrying said bearings, a bolt for securing one of said conductors to the stator and for securing the stator to said lug, and means for securing the other conductor to the stator.

3. In a device of the class described the combination with a stator of a rotor having trunnions fixed thereto and bearing sleeves therefor, means for mounting said trunnions in said bearing sleeves the latter engaging the edge of said stator comprising a supporting member for each trunnion bolted to said stator at a point adjacent the other edge of said stator.

4. In a device of the class described the combination with a stator having recesses located at diametrically opposite points on an edge thereof, of a rotor having trunnions fixed thereto and bearing sleeves therefor, means for mounting said trunnions in said bearing sleeves the latter engaging within the recesses of said stator, comprising a supporting member for each trunnion bolted to said stator only at a point adjacent the other edge of said stator.

5. In a device of the class described, the combination with a stator having recesses located at diametrically opposite points on an edge thereof, of a rotor having trunnions fixed thereto and bearing sleeves therefor, means for mounting said trunnions in said bearing sleeves, the latter engaging within the recesses of said stator comprising a rigid metallic strap for each bearing sleeve and bolted to said stator at a point adjacent the other edge thereof and

adapted to conduct a current to or from said trunnion.

6. In a device of the class described, the combination with a stator having recesses located at diametrically opposite points on an edge thereof, of a rotor having trunnions fixed thereto and bearing sleeves therefor, means for mounting said trunnions in said bearing sleeves the latter engaging within the recesses of said stator comprising a rigid metallic strap for each bearing sleeve and bolted to said stator at a point adjacent the other edge thereof and spring actuated means to effect wiping electrical connections between said fixed strap and movable trunnion whereby said strap is

adapted to conduct a current to or from said trunnion.

7. In a device of the class described, the combination with a stator of two parts with edges thereof in abutment, of a rotor having trunnions fixed thereto and bearing sleeves therefor, means for mounting said trunnions in said bearing sleeves and between the abutting edges of said stator parts comprising a rigid strap for each bearing sleeve and bolted to said stator parts adjacent the other edges thereof whereby said parts are retained in assembled relation.

In testimony whereof I have affixed my signature.

CLARENCE D. TUSKA.
